UNITED STATES PATENT OFFICE.

WALTER JUDD BRIDGES, OF TWO RIVERS, WISCONSIN

AIR-CLEANSING HUMIDIFIER.

Application filed May 22, 1926. Serial No. 111,075.

My invention relates to humidifiers such as are designed for application to the steam, vapor or hot water radiators of domestic heating systems or the like, and it has for 5 its primary object to provide a novel and improved means whereby the air in the room wherein it is located will be positively caused to circulate. Further, the invention comprehends in a device of this 10 character a novel means for purifying the air as it passes therethrough,—and also a very simple and efficient means for controlling the velocity of circulation.

Other objects, economies and advantages 15 of the invention will be readily understood and appreciated as the description proceeds.

The various features of novelty which characterize my invention are pointed out with particularly in the claims annexed to 20 and forming a part of this specification. However,—for a better understanding of the invention, reference should be had to the accompanying drawings in the reading of the following descriptive matter, the drawings 25 illustrating what I now regard as a preferred embodiment. I am aware that the law permits me to make such modifications and departures as fairly fall within the spirit and scope of the invention as claimed.

30 In the drawings,

Figure 1 is a perspective view showing the invention applied to a radiator;

Fig. 2 is a cross section;

Fig. 3 is a longitudinal sectional view;

35 Fig. 4 is a section on line 4—4 of Fig. 3, and

Fig. 5 is a perspective detail of a curtain member and its support.

Referring specifically to the drawings 40 wherein like reference characters designate similar parts in all views, numeral 2 designates generally a rectangular casing having a front wall 3, end walls 4 and a back wall 5. The casing 2 is cabinet like in form and 45 is preferably formed of sheet metal although other materials may be employed if desired. The bottom of the casing is open so that it can be placed over the conventional form of steam or hot water radiator 50 6 as shown in the drawings. Feet 7 are provided whereby to support the casing in such fashion that the lower edges of its walls will be spaced from the floor so as to permit air to freely pass upwardly through 55 the radiator and casing to the outlet 8 which

is in the form of a rectangular opening cut in the front wall 3 from the upper edge thereof.

A lid or closure 9 having an overhanging marginal flange 10 is hinged to the back 60 wall 5 as indicated at 11, it being noted that the flange 10 is designed to snugly embrace the casing walls. At the front of the casing the flange 10 is provided with bearings 12 for the pintles 13 of a damper 14 which 65 is thereby swingingly positioned to close the outlet 8 when the cover 9 is down.

The water reservoir 15 is of elongated rectangular form and has one longitudinal edge provided with a reverted flange 16 70 which is designed to engage the front wall 3 at the lower edge of the outlet 8 as shown. The reservoir 15 is thus supported to lie against the front wall 3 of the casing between the same and the radiator 6. The 75 length of the water reservoir 15 is slightly greater than the length of the outlet opening 8 and its ends extend beyond the planes of the end walls of said opening. This relative arrangement is advantageous as will 80 presently appear. A screen is provided in the form of a cloth like curtain 17 for overlying the opening 8 and it is supported by a U-shaped rod 18 which is removably carried within the reservoir 15. The legs of 85 the U-shaped member 18 are supported by the bottom of the reservoir 15 and flatly bear against the end walls thereof. The legs of 90 said U-shaped member have lateral supporting feet 19 which snugly fit in the reservoir bottom thus preventing any transverse tilting of the member 18 to maintain the horizontal part of the U-shaped member against the front wall 3 above the plane of the outlet opening 8. The curtain 17 is looped as 95 at 17^a to receive rod or member 18 and its width and the length of the horizontal part of member 18 is greater than the length of the outlet 8 so that the latter will be fully 100 covered at all times. Air can therefore, only escape by passing through the curtain 17, and since this curtain is suspended in the container it will be saturated with water at all times and will function as a wick. Air 105 passing through the curtain 17 will not only be humidified, but will also be freed of particles of dirt, dust and the like. Since a constant circulation of air is set up in the room it will be appreciated that after a certain 110 period of use of my humidifier the air of

the room will be substantially free of dust. The path of the circulating air is indicated by the arrows in Fig. 1, the cool air being drawn in through the louver section 20 in the lower part of the front wall 3 and up through the open bottom of the casing 2 as previously explained. The damper 14 can be adjusted to variably control the flow of air out through the outlet 8 and may be held in adjusted position through the medium of a nut 21 threaded upon the pintle 13 and designed to bind against the bearing 12 in a self evident manner.

The cover 9 will preferably be lined with asbestos to prevent it from becoming overheated and so that it will be available for books or the like.

The water reservoir is readily accessible and can be filled upon raising of cover 9 without being removed. As will be evident reservoir 15 can be quickly lifted out of its position and requires no bolts or brackets to hold it in place. Likewise the U-shaped member 18 forms a very simple and convenient means for supporting the curtain 17. Its legs being supported by the bottom of the reservoir 15 and frictionally engaging the end walls, no other supporting or fastening means is necessary.

The part 20^a of the top louver section engages back of reservoir 15 and helps hold it in place against front wall 3. This element 20^a is by no means essential, though desirable.

Having thus described my invention what I claim as new and desire to secure by Letters Patent is:

1. A combined radiator casing and humidifier having front, rear and end walls, said front wall being provided with an outlet opening for the discharge of heat and vapor saturated air, a substantially rectangular water pan, means for supporting said water pan within said casing adjacent the front wall thereof and below said outlet opening, an upstanding carrier having a horizontal portion disposed above the top of said opening and having a base portion supported upon the bottom of said pan, the end of said base portion engaging the rear wall of said pan whereby to hold said carrier in close proximity to the front wall of said pan, an absorbent screen supported upon the horizontal portion of said upstanding carrier and depending into said pan, the width of said screen being co-extensive with the width of said opening, and said upstanding carrier serving to hold said screen against

the front walls of said pan and said casing, and a closure for said opening. 60

2. A combined radiator casing and humidifier having front, rear and end walls, said front wall being provided with an outlet opening for the discharge of heat and vapor saturated air, a substantially rectangular water pan, means for supporting said water pan within said casing in flat contact with the front wall thereof and below said outlet opening, an inverted U-shaped supporting rod removably positioned in said pan, means whereby the legs of said inverted U-shaped supporting rod will be held against swinging movement and in close proximity to the front wall of said pan, said inverted U-shaped rod having its bight portion located above the upper edge of said pan and above the plane of said opening, an absorbent screen supported upon the bight portion of said U-shaped supporting rod and depending into said pan, the width of said screen being co-extensive with the width of said opening, and said inverted U-shaped supporting rod serving to hold said screen against the front walls of said pan. 75

3. A combined radiator casing and humidifier having front, rear and end walls, said front wall being provided with an outlet opening for the discharge of heat and vapor saturated air, a substantially rectangular water pan having its front wall provided with means for removably supporting said pan interiorly of the casing and below said opening, the front walls of said pan and said casing being flatly engaged with each other, an inverted U-shaped supporting rod removably positioned in said pan, the legs of said U-shaped supporting rod being formed with feet designed to flatly rest upon the bottom of said pan and to engage the rear wall thereof whereby the legs of said U-shaped rod will be held against swinging movement and in close proximity to the front wall of said pan, said U-shaped rod having its bight portion located above the upper edge of said pan and above the plane of said opening, an absorbent screen carried by the bight portion of said rod and extending downwardly over the entire area of said opening and into said vaporizing pan, and said inverted U-shaped supporting rod serving to hold said screen against the front walls of said pan and said casing. 100 105

In testimony whereof I affix my signature.

WALTER JUDD BRIDGES.
